his Attorney.

UNITED STATES PATENT OFFICE.

ARTHUR E. SCHUFFENHAUER, OF SOUTH CHICAGO, ILLINOIS.

JOINTER.

1,296,325.

Specification of Letters Patent. Patented Mar. 4, 1919.

Application filed November 23, 1915. Serial No. 63,002.

To all whom it may concern:

Be it known that I, ARTHUR E. SCHUFFENHAUER, a citizen of the United States, and a resident of the city of South Chicago, 5 county of Cook, and State of Illinois, have invented certain new and useful Improvements in Jointers, of which the following is a specification.

My invention relates to jointers, that is to 10 tools employed by bricklayers for removing the surplus mortar between adjacent bricks, smoothing the surface of the mortar, and giving the same a particular shape in order to form a neat and finished joint.

15 The object of my invention is the production of a tool of the character mentioned which will be of simple construction and efficient in use.

Other objects will appear hereinafter.

20 The invention consists in the combinations and arrangements of parts hereinafter described and claimed.

The invention will be best understood by 25 reference to the accompanying drawing forming a part of this specification, and in which,

Figure 1 is a side elevation of a jointer embodying the invention.

Fig. 2 is a top plan view thereof.

30 Figs. 3 and 4 are slightly enlarged sections taken on lines *x-x* and *y-y* respectively of Fig. 1, and

Fig. 5 is a view similar to Fig. 3 showing a slightly modified form of construction.

35 The preferred form of construction, as illustrated in the drawing comprises an elongated metallic body 1 angular in cross section, the outer surfaces thereof being smooth for engagement with the mortar in 40 the operation of the tool. The body 1 is provided with a handle 2 of substantially inverted U-shape, the ends of said handle being shaped to fit in the groove of the body 1 and being reduced to engage with openings 45 formed in said body at the bottom of said groove, as clearly shown in Figs. 1 and 3. In order to lock said ends of the handle 1 to the body of the tool, said ends are upset, the same being made flush with the 50 gaging outer surfaces of the body so as to afford no obstruction in the use of the tool.

The upper horizontal portion of the handle 2 is provided at its under side with a member 4 of wood to increase the width of this 55 portion and constitute a better grip, as will be readily understood. The member 4 is se-

cured to the handle 2 by screws 5 and the under side of said member 4 is rounded, as shown in Fig. 3.

The ends 6 of the body 1 are inclined inwardly or toward the handle and the end surfaces 7 are beveled or inclined toward the engaging surfaces of the body 1, as clearly shown in Figs. 1, 2 and 4.

In using the tool, the same is pressed into 65 engagement with the mortar between the bricks where the joint is to be formed so that the meeting edge of the opposite engaging surfaces of the body 1 of the tool enters between the adjacent edges of the bricks. 70

The tool is then moved longitudinally, as will be readily understood. When this is done, the surplus or protruding mortar will be removed and a smooth neat joint formed 75

which will be V-shaped in cross section or 80 of a form corresponding with that of the body of the tool. Through the inward inclination of the ends of the tool, a sort of shearing action results or in other words the pressure of the tool upon the protruding 85 mortar is distributed along the inclined ends of the tool which prevents tearing or rupturing of the surface of the mortar as might otherwise result were the ends of the tool cut off at right angles. Also, through the 85

beveling or inclination of the end surfaces 7, the severing of the surplus mortar will occur at the forward edges of the surfaces 7 leaving a thickness of material corresponding with that of the sides of the body 90 of the tool which, as the tool advances, will be wiped over the surface of the joint and thus insure the formation of a joint which is perfectly smooth and even.

Also, by reason of the inward inclination 95 of the ends 6 of the tool, points are formed at the ends of the latter which are of utility in the removal of stones or other foreign matter from the mortar, said ends affording an excellent means for gouging out the objectionable foreign matter.

The form shown in Fig. 5 is substantially 105 the same as that described except that in this form the body 1' of the tool is of semi-circular formation whereby, in using the same, a groove or joint of semi-circular formation in cross section will be formed between the bricks instead of a groove V-shaped in cross section as is the case when using a tool of the form first described. The ends of the 110 body 1' will be inclined in precisely the same manner as the ends of body 1 and

the end surfaces beveled or inclined toward the engaging surface of the tool in precisely the same manner as the surfaces 7 of tool 1. The ends of the handle 2' will enter the 5 open side of the body of the tool and will be shaped to conform therewith.

While I have illustrated and described the preferred forms of construction for carrying my invention into effect, these are capable of variation and modification without departing from the spirit of the invention. I, therefore, do not wish to be limited to the 10 precise details of construction set forth, but desire to avail myself of such variations and 15 modifications as come within the scope of the appended claims.

Having described my invention what I claim as new and desire to secure by Letters Patent is:

20 1. A tool of the class described, comprising an elongated body of shell like form the

outer face thereof constituting a smooth engaging surface, the ends of said body being defined by upwardly and inwardly inclined faces intercepting said engaging surface at 25 an obtuse angle, substantially as described.

2. A jointer of the class described comprising an elongated sheet metal body formed of a pair of integral angularly disposed sides, the ends of said sides being upwardly and inwardly inclined, the faces of said ends intercepting the outer faces of 30 said sides at an obtuse angle, substantially as described.

In testimony whereof I have signed my 35 name to this specification in the presence of two subscribing witnesses.

ARTHUR E. SCHUFFENHAUER.

Witnesses:

ARTHUR A. OLSON,
JOSHUA R. H. POTTS.
